UNITED STATES PATENT OFFICE.

WILLIAM V. MILLER, OF TORONTO, ONTARIO, CANADA, ASSIGNOR, BY MESNE ASSIGNMENTS, TO THE SINGER MANUFACTURING COMPANY, OF NEW YORK, N. Y., A CORPORATION OF NEW JERSEY.

SEWING-MACHINE.

972,894.

Specification of Letters Patent. Patented Oct. 18, 1910.

Application filed February 19, 1906. Serial No. 301,824.

To all whom it may concern:

Be it known that I, WILLIAM VELETTE MILLER, a citizen of the United States, and resident of Toronto, in the county of York and Province of Ontario, Canada, have invented certain new and useful Improvements in Sewing-Machines; and I hereby declare that the following is a full, clear, and exact description of the same.

- 10 This invention relates to certain new and useful improvements in that class of sewing machine employed for button sewing, tacking, stayng, and French knot making purposes, and it relates more particularly; 1.
- 15 To an upper-thread-retainer attached to the needle bar, operable means to actuate the upper-thread-retainer to clamp the upper thread and prevent its withdrawal from the needle eye, and other means to automatically
- 20 actuate the upper-thread-retainer to release the upper-thread on the completion of the first stitch of each sewing operation; 2. To an upper-thread-clamp and means to automatically actuate it to engage the upper-
- 25 thread previous to or coincident with the release of the upper-thread-retainer, and securely hold it during the formation of the first stitch and any selected number of stitches thereafter, and then automatically
- 30 actuate it to release the upper-thread so that its end may be sewn into, and prevented from appearing above or below the surface of the work; 3. To a thread-severing-mechanism located below the work-holding-clamp,
- 35 means to automatically position it where the upper-thread-severing-members will enter the loop of the last stitch, of each sewing operation, during the formation thereof, operable means to actuate the thread-severing
- 40 members when positioned within said loop to successively sever the upper and the bobbin threads preferably previous to the release of the work-holding-clamp; and 4. To a bobbin-thread-clamp to securely hold the
- 45 bobbin thread, for the formation of the first stitch of each sewing operation.

For a full understanding of the invention reference is to be had to the following description and to the accompanying drawings, in which,

Figure 1 is a side elevation of a sewing machine, showing the constructive arrangement of the parts; Fig. 2 is a front elevation

of the same. Fig. 3 is a plan view of the under side of the sewing machine showing 55 the first and fourth positions of the operating mechanism for positioning the thread-severing-mechanism. Fig. 3^a is a similar view to Fig. 3, showing the second position, and Fig. 3^b is a similar view to Fig. 3, showing 60 the third position of the operating mechanism. Fig. 4 is a side elevation of the operable means for actuating the oscillating members of the thread-severing-mechanism. Fig. 5 is a plan view showing the first or extreme advance position of the thread-severing-mechanism or the position of the parts preparatory to the downward movement of the needle bar for the first stitch; this being 65 also the fourth position of the thread-severing-mechanism or the position of the parts during the formation of the last stitch of the sewing operation. Fig. 6 is a similar view to Fig. 5, showing the thread-severing-members actuated to sever the upper and bobbin 70 threads. Fig. 7 is a plan view showing the second or intermediate position of the thread-severing-mechanism, this being the position into which the thread-severing-mechanism moves during the upward movement of the needle bar for the first stitch, and the position in which the thread-severing-mechanism is detained during the formation of any selected number of stitches 75 thereafter. Fig. 8 is a plan view showing 80 the third or extreme retracted position of the thread-severing-mechanism. Fig. 9 is a plan view with the slide-plate and related parts removed to show the location of the lower-thread severing-blade when the parts are in 85 the position shown in Fig. 5. Fig. 10 is a similar view to Fig. 9, to show the location of the lower-thread severing-blade when the parts are in the position shown in Fig. 6. Fig. 11 is a similar view to Figs. 9 and 10 to 90 show the location of the lower-thread severing-blade when the parts are in the position shown in Fig. 7. Fig. 12 is a plan view to show the upper-thread-clamp in its inoperative position. Fig. 13 is a similar view to 95 Fig. 12, to show the upper-thread-clamp in its operative position. Fig. 14 is a section on the lines a—a Fig. 12. Fig. 15 is a plan view of the work-holding-clamp. Fig. 16 is a longitudinal section on the lines a—a 100 Fig. 15. Fig. 17 is a plan view of the work-

holding-jaws detached from the related parts. Fig. 18 is a perspective view of the swinging arm for actuating the upper-thread-retainer. Fig. 19 is a perspective view of the upper-thread-retainer in its inoperative position. Fig. 20 is a perspective view of the upper-thread-retainer in its operative position. Fig. 21 is a sectional view on the lines *a—a* Fig. 19. Fig. 22 is a 10 sectional view on the lines *a—a* Fig. 20. Fig. 23 is a sectional view taken at right angles to Fig. 21. Fig. 24 is a perspective view of that part of the needle-bar contained in the upper-thread-clamp, and Fig. 25 is a 15 front elevation of the loop-taker and thread-severing-mechanism.

Like letters of reference refer to like parts throughout the specification and drawings.

20 For the purpose of explaining the construction, operation and purpose of the novel features of the invention they have been shown and described in connection with certain other features of a sewing machine, but 25 as they can be used in connection with a sewing machine of other makes it is not intended that their use should be confined to the particular machine shown and described in the present application, nor is it necessary 30 to describe in detail the construction or operation of any of the parts of the sewing machine except such as are directly related to the present invention.

The upper-thread-retainer.—Before starting 35 the operation of the machine, the needle *a* is threaded and the projecting part of the upper thread *b* is cut to the required length preferably the length of the needle so as to correspond to the distance between the needle eye *c* and the upper-thread-clamp *d*, and the upper-thread-retainer is then set to prevent the withdrawal of the upper thread from the needle eye.

The upper-thread-retainer consists of an 45 annular sleeve *p* mounted on the needle bar *g* near the lower end of the latter, and is slightly greater in diameter than the encircled part of the needle bar, so that it will not cut or bruise the upper thread when 50 clamped between the wall of the sleeve and the surface of the needle bar. Formed in the needle bar *g* is a thread groove *r* and formed in the annular sleeve *p* is a thread aperture *s* to register with the thread-groove *r* when the upper-thread-retainer is set in its 55 inoperative position.

To thread the needle, the annular sleeve is set so that the thread aperture *s* will register with the thread groove *r*, and the upper 60 thread is then conducted from the thread-take-up *t* through the thread aperture and thread groove to the needle eye *c*. When the needle is threaded the annular sleeve is moved into a position in which the thread 65 aperture *s* will be out of line with the thread

groove *r* so that the wall of the annular sleeve *p* can clamp the thread between itself and the surface of the needle-bar, the clamping part of the wall of the annular sleeve being yieldingly held against the corresponding part of the needle-bar by a spring *p⁴* interposed between the wall of the sleeve and a socket in the needle bar diametrically opposite the thread-clamping-parts. Projecting from the outer surface of the annular sleeve *p* is a wing *m*, and opposed to the wing *m* is a reciprocating arm *l* attached to or forming part of the swinging-arm *j* pivotally connected with the lower bearing *k* for the slide-bar *g*. The swinging-arm *j* hangs from the bearing *k* contiguous to the slide-bar *g* and formed in the swinging-arm is a skeleton cam *i* in which travels a stud *h* projecting from the adjacent surface of the slide-bar. The slide-bar *g* is raised by a 85 lifting lever *f* rockable on a fulcrum *p²* projecting from the horizontal arm *p³* of the main frame, and is lowered when the lifting lever is released, by the usual tension spring *g²*. 90

At the completion of each group of stitches, the machine is stopped with the take-up lever *t* in substantially its highest position, at which time the needle is in the initial portion of its downward movement, with the lateral wing *m* of the loose sleeve *p* just below the fixed cam member *u* and at the level of the arm *l* of the swinging member *j*. 95

When the needle is threaded the lifting 100 lever *f* is actuated to raise the spring tensioned slide bar *g*. During the upward movement of the slide-bar the stud *h* travels in the skeleton cam *i* and causes the forward movement of the swinging arm *j* to bring the reciprocating arm *l* into engagement with the wing *m* and rotate the annular sleeve *p* on the needle bar *g*. The rotation of the annular sleeve on the needle-bar moves the thread aperture *s* out of line 110 with the thread groove *r* so that the wall of the annular sleeve *p* will clamp the thread between itself and the needle bar and prevent the thread-take-up *t* withdrawing the upper thread from the needle eye while the 115 needle bar moves downwardly or upwardly for the formation of the first stitch. When the upper-thread-retainer is set to clamp the upper thread the lifting lever is released and the slide bar *g* is lowered by the tension spring *g²*. During the descent of the 120 slide-bar the stud *h* travels downwardly in the skeleton cam *i* and moves the swinging arm *j* and the reciprocating arm *l* rearwardly and out of engagement with the wing *m* to permit of the release of the upper-thread-retainer as hereinafter described. The machine is then set in operation and the needle bar then performs its initial descending and ascending movements with the 125 130

upper-thread-retainer set in its operative position.

As the needle-bar nears the completion of its ascending movement, the wing *m* is engaged by the releasing cam *u* attached to the lower bearing *o* for the needle-bar and this cam as the needle-bar completes its ascending movement automatically restores the wing *m* and annular sleeve *p* to their normal positions to release the upper thread and cause the thread aperture *s* to align with the thread groove *r* so that the thread thereafter may freely pass from the thread-take-up to the needle eye during the continued movement of the needle bar. During the descent of the needle bar, the needle carries the upper thread through the needle aperture *v* in the throat plate *w*, and as the needle bar ascends the beak *x* of the loop-taker, herein represented of the rotating shuttle type, engages the upper thread and draws its free end beneath the throat plate *w* to be engaged by the upper-thread-clamp *d*.

The upper-thread-clamp.—Previous to, or co-incident with the release of the upper-thread-retainer, the upper-thread-clamp *d* is actuated to engage the end of the upper thread and hold it for any selected number of stitches, to prevent the withdrawal of the upper thread through the work, and is again actuated on the completion of the selected number of stitches to release the upper thread so that its "end" can be sewn into the work.

In the under side of the throat plate *w* is an annular counter sunk recess located vertically below the needle bar and extending through the throat plate within the circumference of the annular recess is the needle aperture *v*, see Figs. 5 to 13 inclusive. The upper-thread-clamp *d* is centrally contained in the counter sunk recess *z*, and consists of a hub *a'* and a series of fingers *c'* projecting radially from the hub, and of sufficient length to move across the needle aperture *v* as the upper-thread-clamp revolves.

As shown in Figs. 12, 13 and 14, the thread-clamping part *b*³ of the surface of the recess is located at the side of the needle aperture *v* and at the side of the thread-clamping part *b*³ is a depression *a*³. The upper-thread-clamp *d* is revolved by a spring dog *d'* carried by the slide plate *e'* in the direction indicated by arrow in Figs. 12 and 13, and during its revolution the radial fingers *c'* successively move across the needle aperture to the thread-clamping part *b*³. In the slide plate *e'* are longitudinally disposed slots *e*² and contained in the slots *e*² are guide-blocks *e*³ of wellknown form to direct and limit the movement of the slide plate. Passing through the block *e*³ are screws *e*⁴ which enter the throat plate to fasten the blocks thereto. The screws *e*⁴ have washers *e*⁵ overlapping the edges of the slots and en-

gaging the under surface of the slide plate to slidably connect the slide plate to the throat plate. The slide-plate *e'* derives its reciprocating movements crosswise of the bed-plate from a rotary cam-wheel driven by any wellknown or suitable means, and provided with a cam-groove *h*' entered by a stud at one end of a lever *f'*, fulcrumed intermediate its ends upon a stud-screw *f*² upon the under side of the base *g'* and having its opposite end connected by means of a link *f*³ with a screw-stud *f*² upon the slide-plate *e'*.

The slide plate *e'* is in the position shown in Fig. 5 during the downward movement of the needle bar for the first stitch of each sewing operation, and as the needle bar ascends the slide plate *e'* is moved by the rocking lever *f'* and face cam *h*' from the position shown in Fig. 5, to that shown in Fig. 7. This movement of the slide plate causes the spring dog *d'* to engage one of the radial fingers *c'* and move the finger indicated by the reference numeral 2 across the needle aperture to engage the end of the upper-thread and clamp it between itself and the thread-clamping-part *b*³. The face cam *h*' is formed to arrest the movement of the slide plate and hold it in the position shown in Fig. 7, for any selected number of stitches, so that when the spring dog has moved the radial finger *c'* across and clear of the needle aperture it will hold it opposite the thread-clamping-part *b*³ to clamp the upper thread until the selected number of stitches has been completed. When the selected number of stitches has been completed, the face cam *h*' again actuates the rocking lever to move the slide plate into the position shown in Fig. 8, and cause the spring dog *d'* to complete the motion of the radial finger *c'* by moving it opposite the depression *a*³ where it releases the upper thread so that the end may be sewn into and prevented from appearing above or below the surface of the work. The needle-bar then performs the predetermined number of stitches to complete the sewing operation, and during the formation of the last stitch of the sewing operation the face cam *h*' again actuates the rocking lever *f'* to move the slide plate from the position shown in Fig. 8, to that shown in Fig. 5, where the spring dog *d'* will engage one of the radial fingers *c'* to actuate the upper-thread-clamp during the first stitch of the next sewing operation. Attached to the throat plate *w* is a friction spring *i'* projecting partly across the annular recess *z* and in the path of the radial fingers *c'* with which it engages during the rotation of the upper-thread-clamp to prevent more than one radial finger moving across the needle aperture on each operation of the slide plate and to prevent retrograde movement of the upper-thread-clamp as the

operative upturned extremity of the spring-dog rises over the beveled edge of the previously engaged finger e' in its return movement with the slide-plate from the position shown in Fig. 8 to that shown in Fig. 5.

The thread-severing-mechanism.—In the slide plate e' is a throat aperture j' to register with the needle aperture v when the slide plate is in the position shown in Figs. 5 and 7 to provide for the free movement of the needle during the operation of the needle bar. The slide-plate e' is provided at the end adjacent the path of movement of the shuttle-beak x with a throat-aperture j' at one side of which and arranged longitudinally of and integral with the slide-plate is a blade or finger k' having a sharpened operative knife-edge k^2 and forming what is herein termed for convenience the fixed severing member, which, while movable with the slide-plate at other times, is maintained in fixed or stationary position relative to the stitch-forming mechanism during the thread-severing operation. Fulcrumed to the under side of the slide-plate e' by means of a screw-stud l^2 is the oscillating or vibrating lever l' having at its operative end a blade or finger m' forming a movable upper thread severing member, which preferably corresponds in shape and dimensions with and underlies the fixed severing member k' . When the slide-plate is in the positions shown in Figs. 7 and 8, the movable blade m' registers with the relatively fixed blade k' and is locked in such relation therewith by means to be herein-after described.

Fulcrumed to the under side of the throat-plate v above the slide-plate e' by means of the stationary screw-stud i^2 is an oscillating or vibrating lever r' having at its forward extremity an inclined cutting edge n' forming a severing member for the lower-thread, this lever having a slot s' to register with the guiding cam q' in the adjacent face of the throat plate and forming part of the guiding cam q' is a keeper p' . Formed through the slide plate e' is a curved slot o^s to register with the slot s' in the severing member r' and with the guiding cam q' in the throat plate. Projecting from the upper face of the oscillating severing member l' is a stud o' which extends through slots o^s and s' and enters the guiding cam q' . When the slide plate is in the position shown in Fig. 8, the stud o' is contained in the keeper p' to prevent the movement of the oscillating severing members l' and r' so that there will be no possibility of the severing members moving accidentally or otherwise into the needle path. Inasmuch as the connecting stud o' of the overlying levers l' and r' is disposed intermediate their respective fulcra l^2 and r^2 , it is evident that the movement of the lever l' upon

its fulcrum-stud l^2 will produce by means of the stud o' and slot s' a movement of the lever r' upon its fulcrum r^2 in the opposite direction.

During the formation of the first stitch of each sewing operation, the slide plate is actuated to move the severing members into the position shown in Fig. 5, in which position it is maintained during the initial descent of the needle bar. It is then moved from the position shown in Fig. 5, to that shown in Fig. 7, in which position, it is held during the formation of any selected number of stitches. It is then moved into the position shown in Fig. 8, where it is maintained until the commencement of the formation of the last stitch of the sewing operation. During the formation of the last stitch, the face cam h' actuates the rocking lever f' to move the slide plate from the position shown in Fig. 8 to that shown in Fig. 5, so that the fixed severing member k' and the blade m' of the oscillating severing member l' will enter the needle-thread-loop distended by the shuttle in the final stitch-forming operation. This needle-thread-loop is tightened around the fixed severing member k' and the blade of the oscillating severing member l' by the needle bar and the thread-take-up as they complete their final movements.

The movement of the slide plate from the retracted position shown in Fig. 8, to the extreme advance position represented in Fig. 5, releases the stud o' from the keeper p' , and when released the oscillating severing members l' and r' can be actuated, by means now to be described, to successively sever the upper and bobbin threads respectively, as they move from the positions shown in Figs. 5 and 9, to those shown in Figs. 6 and 10.

The oscillating severing member l' is connected by a link t' to a collar u' immovably fixed on the sliding bar v' actuated by a flexible connection w' from a pedal lever or other usual or well-known power source. Connected to the collar u' and to the base q' is a tension spring e by which the collar is returned to its normal position when released from the influence of the actuating power. It is possible to employ a stationary guide bar v' and slidably mount on the guide bar a spring tensioned collar u' and connect that collar with the pedal lever (not shown) for the same purpose, and operate it in the same way as above stated. When the last stitch is completed and the motion of the needle bar has stopped, the pedal lever is actuated to operate the thread-severing-means. During the actuation of the pedal lever, the collar u' moves the link t' in the direction indicated by arrow in Fig. 3, to move the oscillating severing member l' from the position shown in Fig. 5, to that

shown in Fig. 6, and strain the upper thread against the cutting edge of the fixed severing member upon its farther side from the needle-pole and positively sever it. The strain of the thread-loop by the action of the member m' , as the term implies, involves the employment of a blunt edge of such member to engage the thread upon the side adjacent the needle-hole v , and this is provided in order that the tension imposed upon the tightened thread-loop by the movement of the member m' may serve to part the thread always at the same point and as close as possible to the goods. While the natural tendency of the device would be to sever the thread at the edge of the fixed finger k' farthest from the needle-hole v , the provision of a cutting edge at such point increases materially the uniformity of action of the severing device upon the thread. The oscillating severing member l' as it moves away from the fixed severing member k' engages the lower or shuttle-thread intermediate the shuttle and the needle-hole v and draws off sufficient bobbin thread for the next sewing operation and carries it to the bobbin-thread-clamp located below the slide plate by which it is held until the initial stitch of the next sewing operation, and co-incident with the actuation of the oscillating severing member l' , the oscillating severing member r' moves in the opposite direction toward the needle aperture v and when the bobbin thread is clamped by the bobbin-thread-clamp, severs the bobbin thread above the slide plate. Upon the release of the actuating means for the link t' , the link is restored to its initial position by the action of the tension spring e , and as it returns to its initial position, it returns the oscillating severing members l' and r' from the positions shown in Figs. 6 and 10 to those shown in Figs. 5 and 9 in which positions they and the slide plate remain while the needle bar descends for the first stitch of the next sewing operation.

The face cam h' when it comes into the position shown in Fig. 3, actuates the rocking lever to move the slide plate into the position shown in Fig. 5, which may be termed the first and fourth positions of the operating mechanism as the slide plate and related parts are in the position shown in Fig. 5, when the needle bar commences the downward movement for the first stitch of each sewing operation, and they are in the same position while the needle bar completes the upward movement of its final stroke on the formation of the last stitch of each sewing operation. From the position shown in Fig. 3, the face cam h' moves into the position shown in Fig. 3^a, to move the slide plate from the position shown in Fig. 5, to that shown in Fig. 7, which may be termed the second or intermediate position of the oper-

ating parts as the slide plate is permitted to remain stationary in this position until the selected number of stitches have been completed. From the position shown in Fig. 3^a, the cam moves to the position shown in Fig. 3^b, which may be termed the third position of the operating mechanism, in which position the slide plate is held stationary until the remaining stitches have been completed. From the position shown in Fig. 3^b, the cam moves to the position shown in Fig. 3, to restore the slide plate and related parts to the position shown in Fig. 5. This makes a complete revolution of the face cam and a complete series of operations of the slide plate.

The bobbin-thread-clamp. The bobbin-thread-clamp y' is secured to the under side of the throat plate w and is located in the path of the oscillating severing member l' when positioned as shown in Figs. 5 and 6, so that as the oscillating severing member l' moves away from the fixed severing member, it will draw off sufficient bobbin thread for the initial stitch of the next sewing operation and carry it beneath the bobbin-thread-clamp. The bobbin-thread-clamp consists of a spring pressed arm y^2 fastened to the throat plate at the side of the slide plate and when the oscillating severing member carries the bobbin thread to it, it clamps the bobbin-thread between itself and the slide plate and securely holds the bobbin thread until it is withdrawn by the operation of the stitch forming mechanism. The relation of these parts is such that when the blade m' carries the under or bobbin thread between the clamping member y' and the slide-plate e' , the thread is nipped with such force as to maintain taut the portion connected with y' to work after the chopping action of the severing member n' , thereby effectively preventing the drawing off from the bobbin of more under thread than that measured off by the lever l' . Upon the withdrawal of the lever l' from beneath the spring-pressed clamping member y' , the latter is permitted to approach the slide-plate e' sufficiently to maintain a slight pressure upon the severed bobbin thread, so as to retain it temporarily, but to readily release it as soon as it is engaged by a loop of needle-thread in the production of the first stitch of a succeeding series.

The work-holding-clamp. The lifting lever f is preferably connected with the pedal lever by a flexible connecting member x^2 so adjusted as to cause the actuation of the lifting lever subsequent to the actuation of the thread-severing-mechanism, to cause the lifting lever to raise the work-holding-clamp for the removal of the work after the upper and bobbin threads have been severed. The work-holding-clamp consists of two work-holding-jaws z' and z^2 , pivotally and inde-

pendently connected to a clamp plate z^3 by fulcrum screws a^2 and b^2 arranged on opposite sides of the medial line of the clamp plate and on an imaginary line intersecting the medial line at right angles thereto, as shown in dotted line in Fig. 15. Formed on the work-holding-jaw z' is a male spur tooth c^2 and formed on the work-holding jaw z^2 is a female tooth d^2 into which enters the male tooth c^2 . The center of the pitch line of these teeth is at the point of intersection of the medial and imaginary lines above mentioned and from this center the work-holding-jaws open and close in unison. Normally pressing the work holding jaws together are tension springs f^2 connected to the clamp plate z^3 by a screw g^2 . Locking the work-holding-jaws in their closed position is a tapering locking pin h^2 which passes through the clamp plate z^3 between the work-holding-jaws in rear of their fulcrum screws. Holding the tapering locking pin in position between the rear ends of the work-holding jaws is a spring tensioned locking bar h^3 . Connecting the tapering locking pin with the lifting lever f is a link i^2 . During the actuation of the lifting lever f , the link raises the tapering locking pin to release the work-holding-jaws, and to lift the jaws from the work by the engagement of a shoulder j^2 formed on the tapering locking pin with the under side of the clamp plate z^3 . To gage the width of the space between the jaws when closed, the clamp plate is formed at its front end with a longitudinally disposed slot in which is longitudinally adjustable a spacing stud k^2 to engage the work-holding-jaws in front of the fulcrum screws a^2 and b^2 to limit their closing movement.

The details of the operating mechanism can be altered without departing from any of the principles of the invention.

Having thus fully described my invention what I claim as new and desire to secure by Letters Patent is;

1. In a sewing machine, the combination with stitch-forming mechanism and work-holding means, of a thread-severing mechanism comprising relatively movable thread-engaging members, automatically acting means for operating said members whereby one of them performs an initial movement to enter a loop of a stitch formed by the stitch-forming mechanism, and manually operated means for actuating the other of said members transversely to said initial movement to sever the thread.

2. In a sewing machine, the combination with stitch-forming mechanism comprising a reciprocating needle and a co-operating loop-taker, of a thread-severing device comprising a slide-plate, a severing member fixed thereon and movable therewith adjacent the needle-path, a movable severing

member pivotally connected to the slide-plate, automatically acting means for operating the slide-plate to position the fixed and oscillating severing members in the needle-thread-loop distended by the loop-taker in the production of the last stitch of a group of stitches, and manually operated means to actuate the oscillating severing member to sever the thread.

3. In a sewing machine, the combination with stitch-forming mechanism comprising a reciprocating needle and complementary lower-thread mechanism, of a thread-severing device comprising a slide-plate, a severing member fixed thereon and movable therewith adjacent the needle-path, a movable severing member pivotally connected to the slide-plate, automatically acting means for operating the slide-plate to position the fixed and oscillating severing members in the needle-thread loop of the last stitch of a group of stitches, manually operated means to actuate the oscillating severing member to sever the needle-thread, a second pivotally mounted severing member movable differentially in respect of the first-named pivotally-mounted severing member, and means whereby the second-named severing member is operated to sever the lower thread.

4. In a sewing machine, the combination with stitch-forming mechanism comprising a reciprocating needle and complementary lower-thread mechanism, of a thread-severing device comprising a slide-plate, a severing member fixed thereon and movable therewith adjacent the needle-path, a movable severing member pivotally connected to the slide-plate, automatically acting means for operating the slide-plate to position the fixed and oscillating severing members in the needle-thread-loop of the last stitch of a group of stitches, manually operated means to actuate the oscillating severing member to sever the needle-thread, a second pivotally mounted severing member movable differentially in respect of the first-named pivotally-mounted severing member, and means whereby the second-named severing member is operated to sever the lower thread.

5. In a sewing machine, the combination with stitch-forming mechanism comprising a reciprocating needle and complementary lower-thread mechanism, of a thread severing device comprising a slide-plate, a severing member fixed thereon and movable therewith adjacent the needle-path, a movable severing member pivotally connected to the slide-plate, automatically acting means for operating the slide-plate to position the fixed and oscillating severing members in the needle-thread-loop of the last stitch of a group of stitches, manually operated

- means to actuate the oscillating severing member to sever the needle-thread, a second severing member pivotally mounted upon a stationary fulcrum, and an operative connection intermediate said pivotally mounted severing members whereby the actuation of the one in severing the needle-thread produces the actuation of the other to sever the lower thread.
10. 6. In a sewing machine, the combination with stitch-forming mechanism comprising a reciprocating needle and complementary lower-thread mechanism, of a thread-severing device comprising a slide-plate, a severing member fixed thereon and movable therewith adjacent the needle-path, a movable severing member pivotally connected to the slide-plate, automatically acting means for operating the slide-plate to position the 15 fixed and oscillating severing members in the needle-thread-loop of the last stitch of a group of stitches, manually operated means to actuate the oscillating severing member to sever the needle-thread, a second severing member 20 overlying the first-named pivoted severing member and pivotally mounted upon a stationary fulcrum and provided with a cam-slot, and a stud carried by the first-named pivoted severing member and entering the 25 cam-slot of the second-named pivoted severing member whereby the latter is operated to sever the lower thread.
7. In a sewing machine, the combination with stitch-forming mechanism comprising a reciprocating thread-carrying needle and a coöperating loop-taker carrying a lower thread, of a thread-severing device comprising a carrier, upper-thread severing members respectively fixedly and movably 30 mounted thereon, automatically acting means whereby said severing members are introduced into a needle-thread-loop in the production of the last of a succession of stitches, means for shifting the movable 35 severing member laterally for successively severing the needle-thread-loop and engaging and drawing off the lower thread for a succeeding stitching operation, a lower-thread severing member, and means for 40 actuating the same to sever the lower thread.
8. In a sewing machine, the combination with stitch-forming mechanism comprising a reciprocating thread-carrying needle and a coöperating loop-taker carrying a lower 45 thread, of a thread-severing device comprising a carrier, upper-thread severing members respectively fixedly and movably mounted thereon, automatically acting means whereby said severing members are introduced into a needle-thread-loop in the production of the last of a succession of stitches, means for shifting the movable severing member laterally for successively severing the needle-thread-loop and engaging and drawing off the lower-thread for a succeed-
- ing stitching operation, a lower-thread severing member, and an operative connection between said movable severing member for the needle-thread and the severing member for the lower thread whereby the latter is 70 actuated by the operative movement of the former in drawing off lower thread.
9. In a sewing machine, the combination with stitch-forming mechanism comprising a reciprocating thread-carrying needle and a coöperating loop-taker carrying a lower thread, of a thread-severing device comprising a carrier, upper-thread severing members respectively fixedly and movably mounted thereon, automatically acting means whereby said severing members are introduced into a needle-thread-loop in the production of the last of a succession of stitches, a lower-thread clamping device, means for shifting the 80 movable severing member laterally for successively severing the needle-thread-loop and engaging and drawing off the lower thread and introducing the same into the lower-thread clamp, a lower-thread severing member adapted to engage the lower thread intermediate said clamp and the work, and means for actuating the same to sever the lower thread.
10. In a sewing machine, the combination with a reciprocating thread-carrying needle and a coöperating loop-taker carrying a lower thread, of a thread-severing device comprising a reciprocating slide-plate, a severing member fixed thereon, a severing member pivotally connected to the slide-plate and arranged to normally register therewith, means for actuating the slide-plate to position the fixed and pivoted severing members in the needle-thread-loop of the last stitch of a group, means for actuating the pivoted severing member to strain the needle-thread against the fixed severing member and to engage and deflect the lower thread extending from the loop-taker to the 100 work, a second severing member, and means for actuating the second severing member to sever the lower thread while held in a strained condition by the first-named severing member.
11. In a sewing machine, the combination with a reciprocating thread-carrying needle and a coöperating loop-taker carrying a lower thread, and a throat-plate having a needle-aperture, of a thread-severing device comprising a reciprocating slide-plate having a throat at the end adjacent the needle-aperture of the throat-plate and an upper thread severing member fixed thereon at one side of said throat, an upper-thread severing member pivotally connected to the slide-plate and arranged to normally register with the fixed severing member, a lower-thread severing member movable across the needle-aperture in the throat-plate, means for 115 120 125 130

- actuating the slide-plate to position the upper-thread severing members in the needle-thread-loop of the last of a succession of stitches, and means for actuating the pivoted upper-thread and movable lower-thread severing members for severing the respective threads.
12. In a sewing machine, the combination with a reciprocating thread-carrying needle and a coöperating loop-taker carrying a lower thread, and a throat-plate having a needle-aperture, of a thread-severing device comprising a reciprocating slide-plate having a throat at the end adjacent the needle-aperture of the throat-plate and an upper-thread severing member fixed thereon at one side of said throat, an upper-thread severing member pivotally connected to the slide-plate and arranged to normally register with the fixed severing member, a lower-thread severing member fulcrumed to the throat-plate, means for automatically actuating the slide-plate to position the upper-thread severing members in the needle-thread-loop of the last stitch of a succession of stitches, and means for actuating the pivoted upper-thread and movable lower-thread severing members for successively severing the upper and lower threads.
13. In a sewing machine, the combination with stitch-forming mechanism comprising a reciprocating thread-carrying needle and a coöperating loop-taker, a throat-plate having an aperture through which said needle reciprocates, and a work-holder, of a thread-severing device comprising a reciprocating slide-plate disposed beneath the work-holder and having a throat adapted to register with the needle-aperture of the throat-plate, a severing member fixed upon the slide-plate at the side of the throat and extending in the direction of reciprocation of the slide-plate and adapted to enter a needle-thread loop distended by the loop-taker, an auxiliary severing member movably mounted upon the slide-plate, and means for actuating said movable member to strain the thread against the fixed severing member and thereby cause the severing of the same.
14. In a sewing machine, the combination with stitch-forming mechanism comprising a reciprocating thread-carrying needle and a coöperating loop-taker, a throat-plate having an aperture through which said needle reciprocates, and a work-holder, of a thread-severing device comprising a reciprocating slide-plate disposed beneath the work-holder and having a severing member fixed thereto, an oscillating severing member fulcrumed to the slide-plate and normally registering with the fixed severing member, means for actuating the oscillating severing member, a second differentially movable severing member, and a connection intermediate the movable severing members whereby the oper-

ative movement of one is communicated to the other with an interval between their severing actions.

15. In a sewing machine, the combination with stitch-forming mechanism comprising a reciprocating thread-carrying needle and a coöperating loop-taker, a throat-plate having an aperture through which said needle reciprocates, and a work-holder, of a thread-severing device comprising a reciprocating slide-plate beneath the work-holder and having a severing member fixed thereto and provided with a slot, an oscillating severing member fulcrumed to the slide-plate and normally registering with the fixed severing member, a stud carried by said oscillating severing member and projecting through the slot in the slide-plate, a second severing member having a slot therein for said stud, whereby the second-named severing member can be actuated by the oscillation of the first-named severing member, and means for locking said severing members in one extreme position of the slide-plate.

16. In a sewing machine, the combination with stitch-forming mechanism comprising a reciprocating thread-carrying needle and a coöperating loop-taker, a throat-plate having an aperture through which said needle reciprocates, and a work-holder, of a thread-severing device comprising a reciprocating slide-plate beneath the work-holder and having a severing member fixed thereto and provided with a slot, an oscillating severing member fulcrumed to the slide-plate and normally registering with the fixed severing member, a stud carried by said oscillating severing member and projecting through the slot in the slide-plate, a second severing member having a slot therein for said stud, whereby the second-named severing member can be actuated by the oscillation of the first-named severing member, and means for locking said severing members in one extreme position of the slide-plate.

17. In a sewing machine, the combination with stitch-forming mechanism comprising a reciprocating thread-carrying needle and a coöperating loop-taker, a throat-plate having an aperture through which said needle reciprocates and a cam-groove having a contraction at one end and an enlargement at the other end, and a work-holder, of a thread-severing device comprising a reciprocating slide-plate beneath the work-holder and having a severing member fixed thereto and provided with a slot, an oscillating severing member fulcrumed to the slide-plate and normally registering with the fixed severing member, a stud carried by said oscillating severing member and projecting through the slot in the slide-plate

and into said cam-groove of the throat-plate, and a second severing member having a slot therein for said stud, whereby the second-named severing member can be actuated by the oscillation of the first-named severing member.

18. In a sewing machine, the combination with stitch-forming mechanism including a reciprocating needle and a coöperating loop-taker, and a throat-plate having an aperture through which said needle reciprocates, and provided adjacent thereto on the under side with a projection affording a stationary clamping member and an adjacent depression, of a thread-severing mechanism comprising a reciprocating slide-plate carrying upper-thread severing members, a revolute clamping member having spaced fingers movable across the needle-aperture for engaging the upper thread and clamping it between itself and the stationary clamping member, and means carried by said slide-plate for imparting to the revolute clamping member step-by-step movements in one direction.

19. In a sewing machine, the combination with stitch-forming mechanism including a reciprocating needle and a coöperating loop-taker, and a throat-plate having an aperture through which said needle reciprocates and provided adjacent thereto on the under side with a projection affording a stationary clamping member and an adjacent depression, of a thread-severing mechanism comprising a reciprocating slide-plate carrying upper-thread severing members, a revolute clamping member having spaced fingers movable across the needle-aperture for engaging the upper thread and clamping it between itself and the stationary clamping member, means for advancing the slide-plate to carry said severing members to operative position and for retracting the same in two stages of movement, and means carried by said slide-plate for imparting to the revolute clamping member during the retraction of the slide-plate a two-stage operative movement whereby the needle-thread is successively clamped upon the stationary clamping member and thereafter released at the adjacent depression in the throat-plate.

20. In a sewing machine, the combination with stitch-forming mechanism including a reciprocating needle and a coöperating loop-taker, and a throat-plate having an aperture through which said needle reciprocates and provided adjacent thereto on the under side with a projection affording a stationary clamping member and an adjacent depression, of a thread-severing mechanism, a revolute clamping member having spaced fingers movable across the needle-aperture for engaging the upper thread and clamping it between itself and the stationary clamping member, automatically acting means for ac-

tuating the revolute clamping member in two separate stages to first engage and hold the needle-thread for a selected number of stitches and to thereafter release the same, and controlling means for said revolute member.

21. In a sewing machine, the combination with stitch-forming mechanism including a reciprocating needle and a coöperating loop-taker, and a throat-plate having an aperture through which said needle reciprocates and provided adjacent thereto on the under side with a projection affording a stationary clamping member and an adjacent depression, of a thread-severing mechanism, a revolute clamping member having spaced fingers movable across the needle-aperture for engaging the upper thread and clamping it between itself and the stationary clamping member, automatically and positively acting means for actuating the revolute clamping member in two separate stages to first engage and hold the needle-thread for a selected number of stitches and to thereafter release the same, and controlling means for imposing a frictional drag upon said revolute member to prevent both overthrow and retrograde movement of the latter.

22. An upper thread-clamp for a sewing machine, comprising a throat-plate having an annular recess in the lower side thereof and a needle aperture contiguous to and within the rim of the recess, a clamping member mounted to revolve within the recess and having a series of fingers successively and intermittently movable across the needle-aperture, means for intermittently actuating the clamping member consisting of a slide-plate, a spring-pressed detent-dog carried thereby to successively engage the fingers of the revolute clamping member, means for actuating the slide-plate to rotate the clamping member a distance of one finger across the needle-aperture on each operation of the thread-severing means, and to hold it stationary so that it will engage and hold the upper thread for a selected number of stitches on the next operation of the stitch-forming mechanism, and then actuate it on the completion of the selected number of stitches to release the thread.

23. An upper thread clamp for a sewing machine, comprising a throat-plate having an annular recess in the lower side thereof and a needle aperture contiguous to and within the rim of the recess, a clamping member mounted to revolve within the recess and having a series of fingers successively and intermittently movable across the needle aperture, means for intermittently actuating the clamping member, consisting of a slide-plate and a spring-pressed detent-dog carried thereby to successively engage the fingers of the revolute clamping member, means for actuating the slide-plate to

rotate the clamping member a distance of one finger across the needle-aperture on each operation of the thread-severing means, and to hold it stationary so that it will engage 5 and hold the upper thread for a selected number of stitches on the next operation of the stitch-forming mechanism, and then actuate it on the completion of the selected number of stitches to release the thread, and 10 a detent means to frictionally engage the clamping member.

24. In a sewing machine, the combination with stitch-forming mechanism including a reciprocating needle-bar, of a thread-retainer 15 upon said needle-bar, manually controlled means for actuating the thread-retainer whereby the thread may be clamped previous to the initial descent of the needle-bar, and means independent of said actuating 20 means for releasing the thread in the initial ascent of the needle-bar for each sewing operation.

25. In a sewing machine, the combination with the needle-bar having a thread-groove 25 therein, of a thread-retainer consisting of a sleeve rotatably mounted upon the needle-bar and having a thread-aperture therethrough registering with the thread-groove in the needle-bar when the thread-retainer 30 is inoperative, and means to position the thread-retainer to displace the thread-aperture from alinement with the thread-groove.

26. In a sewing machine, the combination with the needle-bar having a peripheral 35 thread-groove at its lower end, of a thread-retainer consisting of a sleeve loosely mounted on the needle-bar and having a thread-aperture to register with the said thread-groove when the thread-retainer is in its inoperative position, means to yieldingly press 40 the wall of the sleeve adjacent to the thread-aperture against the needle-bar, and means to move the sleeve to position the thread-aperture where it will be out of register 45 with the thread-groove.

27. In a sewing machine, the combination with a needle-bar having a peripheral thread-groove near its lower end, of a 50 thread-retainer consisting of a sleeve loosely mounted upon the needle-bar and having a thread-aperture to register with the said thread-groove when the thread-retainer is inoperative, a spring within the sleeve to yieldingly hold the wall of the thread-retainer adjacent to the aperture against the needle-bar, a projection from the sleeve and actuating means to engage the projection and position the sleeve where its wall can clamp the thread, and other means to automatically engage the projection and position 55 the sleeve where it will release the thread.

28. In a sewing machine, the combination with a needle-bar having a peripheral thread-groove near its lower end, of a 60 thread-retainer consisting of a sleeve loosely

mounted upon the needle-bar and having a thread-aperture to register with the said thread-groove when the thread-retainer is inoperative, a spring within the sleeve to yieldingly hold the wall of the thread-retainer 70 adjacent to the aperture against the needle-bar, a projection from the sleeve, a lifting lever, a reciprocating cam actuated by the lever to engage the projection of the thread-retainer and position the sleeve of 75 the latter on the needle-bar to clamp the thread, and a stationary cam to engage the projection of the thread-retainer and restore the sleeve to inoperative position.

29. In a sewing machine, the combination 80 with the needle-bar, of an upper-thread retainer mounted thereon, a projection for the upper-thread retainer, a slide-bar, a skeleton-cam pivotally connected to the lower bearing of the slide-bar, a stud for the slide-bar 85 operating in the skeleton-cam, a reciprocating arm actuated by the skeleton-cam to engage the projection of the thread-retainer to position the thread-retainer on the needle-bar where it will clamp the thread, and a stationary cam connected to the lower bearing 90 of the needle-bar to engage the projection of the thread-retainer and restore the latter to its inoperative position.

30. In a sewing machine, the combination 95 with a reciprocating thread-carrying needle and a coöperating loop-taker carrying a lower thread, of a stationary thread-clamping member, means for drawing off lower thread and carrying it beneath the thread-clamping member and coöperating therewith in holding the thread taut, and an independently actuated member for severing the thread so held.

31. In a sewing machine, the combination 105 with a reciprocating thread-carrying needle, and a coöperating loop-taker carrying a lower thread, of an upper-thread severing device including operative members adapted to enter a loop of needle-thread, a lower-thread severing device, an operative connection between the upper and lower-thread severing devices and common manually-operated means for actuating the same to sever the upper and lower threads, a needle-thread clamp independent of the upper-thread severing device, and actuating means therefor carried by the latter, and a multi-throw cam and connections between the same and the upper-thread severing device 115 whereby the latter is advanced to enter the needle-thread loop preparatory to manual actuation to sever the threads, the upper-thread device is thereafter partially retracted and the end of the succeeding needle-thread loop is clamped, and said severing device is finally retracted to initial position and the needle-thread-end finally released. 120

32. In a sewing machine, the combination 125 with stitch-forming mechanism including

a reciprocating needle-bar, of a thread-retainer upon said needle-bar, manually controlled means for actuating the thread-retainer whereby the thread may be clamped previous to the initial descent of the needle-bar, and automatically acting means for releasing the thread in the initial ascent of the needle-bar for each sewing operation.

33. In a sewing machine, the combination with stitch-forming mechanism including a reciprocating needle-bar, of a thread-retainer upon said needle-bar, means for actuating the thread-retainer whereby the thread may be clamped previous to the initial descent of the needle-bar, and positively acting means operating upon the thread-retainer for insuring the release of the thread in the initial ascent of the needle-bar for each sewing operation.

34. In a sewing machine, the combination with stitch-forming mechanism, including a reciprocating needle-bar, of a thread-retainer upon said needle-bar comprising a movable member having a projection, a movable operating member mounted independent of said needle-bar, means for throwing said operating member into and out of the path of reciprocation of the projection of said thread-retainer in its travel with the needle-bar for effecting the clamping of the needle-thread, and a fixed operating member secured within the path of movement of said projection while the thread-retainer is in

clamping position for throwing the latter into retracted position.

35. In a sewing machine, the combination with stitch-forming mechanism, including a reciprocating needle-bar, of a thread-retainer upon said needle-bar comprising a movable member having a projection, a movable operating member mounted independent of said needle-bar, manually controlled means for throwing said operating member into and out of the path of reciprocation of the projection of said thread-retainer in its travel with the needle-bar for effecting the clamping of the needle-thread, and a fixed operating member secured within the path of movement of said projection while the thread-retainer is in clamping position for throwing the latter into retracted position.

36. In a sewing machine, the combination with stitch-forming mechanism including a reciprocating needle-bar, of a thread-retainer upon said needle-bar, a needle-thread severing device, means for actuating said severing device, and manually controlled means for actuating the thread-retainer to clamp the needle-thread subsequent to the actuation of said thread-severing device.
